E. R. LINEHAN

STOOL RING COVER

Filed March 3, 1924

INVENTOR:
Edwin R. Linehan
BY *A. M. Larsen*
ATTORNEY.

UNITED STATES PATENT OFFICE.

EDWIN R. LINEHAN, OF RIVER FALLS, WISCONSIN.

STOOL-RING COVER.

Application filed March 3, 1924. Serial No. 696,549.

To all whom it may concern:

Be it known that I, EDWIN R. LINEHAN, a citizen of the United States, residing at River Falls, in the county of Pierce and State of Wisconsin, have invented certain new and useful Improvements in Stool-Ring Covers, of which the following is a specification.

My invention relates to a sanitary appliance for toilet bowls and the object is to provide a simple covering device for the rings or seat portion of such bowls and made of such material as can be readily washed down through the sewer by the regular flushing means.

The accompanying drawing is a top view of my paper cover showing its flaps 15 both as normally cut and in dotted line as folded partly under the ring of the toilet seat. Referring to the drawing by reference numerals, the invention consists of a sheet 11 of suitable paper cut, as shown, to the general outline of the top of a toilet bowl and the seat ring hinged to and normally resting on the bowl, which arrangement is so well known that no further showing or description is deemed here necessary, except to say that the ring is usually hinged to the rear top portion of the bowl by two spaced hinges between which the rear flap 13 of the paper cover 11 is placed and thus held against lateral displacement upon the ring.

Said paper cover is formed with a large aperture 12 corresponding to the usual main

aperture in the seat ring (not shown), and has near its front end a pair of flaps 15, preferably formed of a single flap by slitting it at 16.

These flaps 15 are adapted to be folded downward and outward as shown in dotted line, so as to be held between the top of the bowl and the seat ring, or rubber bumpers 10 fixed on the ring will bear upon the paper cover.

In the operation or use of the device, each person using the seat places a clean paper cover 11 on it and before leaving the place removes said cover down into the bowl, so that the next person can place the next clean sheet on the seat.

What I claim is:—

A seat ring cover for toilet bowls comprising a sheet of paper cut to conform to the general outline of the seat ring, a rearwardly extending, integral flap on said cover adapted to be inserted and held between the hinges of the seat ring to hold the rear part of the ring cover in place; said sheet having an aperture conforming to the shape of the rear part of the bowl opening, said sheet being split longitudinally forward of said aperture to form two adjacent flaps both adapted to be bent downwardly and horizontally under the seat ring and there engaged between the bowl and said seat ring, substantially as and for the purpose set forth.

In testimony whereof I affix my signature.

EDWIN R. LINEHAN.
